FITTING FOR TIGHTENING, HOLDING AND
RELEASING A TENNIS NET OR OTHER
CORD OR WIRE UNDER STRAIN

William Grenville Boyd, Ramsgate, England

Application June 28, 1934, Serial No. 732,909
In Great Britain November 6, 1933

6 Claims. (Cl. 273—29)

This invention relates to means for tightening, holding and releasing a tennis net or other cord or wire under strain and has for its object to provide an improved construction and arrangement embodying frictional locking members operated by a hand lever, movement of which in one direction tends to taunt the cord or wire and lock same and in the opposite direction to effect a releasing movement.

10 The present invention consists in the provision of means for straining, locking and releasing a cord or wire mounted within a hollow straining post and co-operating with the parallel internal walls or surfaces of said post to function.

15 Means are also provided whereby a hand operating lever can drop into its inoperative position within the substance of the post leaving only a small external part for gripping when required for use.

20 Reference will now be made to the accompanying drawings which illustrate by way of example constructions according to the invention and in which:—

Fig. 1 is a part sectional elevation of the invention,

Fig. 2 is a side view of Fig. 1.

Fig. 3 shows detail of upper gripping member, Fig. 4 shows detail in part sectional elevation of modification.

30 Fig. 5 shows the mechanism of Fig. 4 with the operative parts in their folded condition within the straining post.

According to the drawings the straining post 1 is conveniently formed as a hollow member with an internal rectangular space, the opposed sides 2 having parallel relationship as shown by inset section in Fig. 1. The invention is not limited to the rectangular section of the interior of the post, the main requirement being that the hollow parts have parallel sides and sufficient internal space to accommodate the gear.

The post 1 has a pulley 3 mounted at its head in normal manner over which the cord 4 passes and is provided with a slot 5 running centrally up the rear side of the post from the base. The base of the post is intended to be held in a socket or equivalent known securing member not shown. Referring to Fig. 1 the mechanism for straining is inserted within the interior of the post 1, from the base, and is brought into a position whereby the cord can be engaged by the upper gripping member 6. This member 6 is formed of a little greater length than the distance apart of the parallel sides 2 so that its shoulders 6a can engage the sides with slight angularity. In the

form shown, see Fig. 3, a central part 7 extends forward of the shoulder 6a and protrudes through the slot 5 in the post 1 and is provided with a straining hook 8 on its upper extremity and projection 9 on its lower extremity. The member 6 is connected to the inner end of the operating lever 10 by pivoted link 11. The lever 10 is pivoted at 14 to the rear end of the lower gripping device 12 and is further provided with a loop or catch 13, the latter being designed to be placed over the projection 9 on member 6.

The operation of this form of the invention is as follows:—

The mechanism for straining being inserted within the post the cord 4 which is formed with a loop is placed under the hook 8, and the lever 10 raised. This has the effect of causing the lower gripping device 12 to jam against the sides 2 of the post 1 and further movement upward of the lever 10 on its fulcrum pivot 14 draws down the link 11 and upper gripping member 6 and thereby strains the cord 4. When the lever 10 reaches the end of its maximum useful travel the upper gripping member 6 under tension from the cord is caused to jam and remain in a locked position. Movement downward of the lever 10 now releases the lower gripping member 12 which is then free to take up a lower position with the handle depressed. Immediately, however, the lever 10 is raised the lower gripping member 12 jams again giving a stationary fulcrum for the lever 10 to draw down the upper gripping member 6 and with it the cord 4. This operation is repeated until the desired tension is obtained on the cord 4. To release the cord holding device the lever 10 is raised allowing the loop 13 to engage the hook part 9 when the upper (and lower) gripping members are freed, and the mechanism moves upward within the post.

Figs. 4 and 5 show details of a modification in which the loop 13 is dispensed with, and the hook 9 omitted from the upper gripping member 6, allowing only the cord hook 8 and the end of the handle to appear as parts external to the straining post. In this form the upper gripping member 6 is provided with the cord hook 8 and is pivoted to link 11 which carries an upsetting arm 11a, the end of link 11 remote from gripping member 6 being pivoted to lever 10. Lever 10 carries a second link 11b pivoted to the lower gripping member 12, the latter being formed with a trip finger 12a which protrudes from the slot 5 only when the cord is being taunted.

The operation of this form of the invention is similar to that of the form previously described

except straining is effected by a downward movement of the lever 10 and that to release the top gripping member the member 12 is tripped and the lever is smartly pushed in when the arm 11a contacts with the back part of member 6 and frees it from engagement thus allowing the whole gripping device to slide upwards within the cavity of the post.

When in operation the cord is tautened and the upper gripping member is in its condition of fixity, the whole of the remainder of the actuating gear is free to fall and occupy the position shown in Fig. 5.

From the foregoing it will be observed that a cord straining and fixing device is provided whose operative parts are within a cavity of the post, and that the actuating lever when not in use is free to fall to its inoperative position and lie mainly out of sight and create no external obstruction. Further, the greater the tension on the wire or cord the greater the locking force exerted upon the cord gripping member.

I claim:—

1. A straining, locking and releasing device for cords, wires and the like, comprising a hollow straining post having parallel internal walls, and having a slot formed in one of said walls, upper and lower gripping elements engageable with said walls, the upper element extending through said slot and having means thereon for cord attachment, an operating lever pivotally connected to the lower element, and a link connecting an end of said lever to the upper element and operative by up and down movements of the lever to cause the gripping members alternately to lock and release and thereby descend within the post and thereby tauten the cord.

2. A tightening device of the character described comprising a hollow post having opposed parallel walls, and having a slot formed in one of said walls, upper and lower gripping elements extending between said walls and inclined downwardly toward one of said walls, the lower end of one of said elements having a portion for attachment thereto of the part to be tightened, and an operating lever extending through said slot and connected at different points in its length to the lower ends of said elements and operative, when swung in one direction, to cause one of said elements to grip said walls and the other element to shift longitudinally thereof.

3. A tightening, locking and releasing device of the class described comprising a hollow post having opposed parallel walls one of which is provided with a longitudinal slot, upper and lower gripping elements within the post both extending transversely thereof between said parallel walls and inclined downwardly toward the slotted wall, a portion of one of said elements extending through said slot and having means for the attachment thereto of the part to be tightened, and an operating lever extending through said slot and pivotally connected at different points in its length to the lower ends of said inclined gripping elements to move one of them into gripping engagement with said opposed walls and

to move the other gripping element in a direction to release it from said walls when said lever is swung in one direction.

4. A tightening device comprising a hollow post having opposed parallel walls one of which is provided with a longitudinal slot, a pair of gripping elements within the post both extending in inclined directions transversely thereof between said parallel walls and engageable therewith, the length of said elements being greater than the distance between said opposed walls, one of said elements having means thereon for the attachment thereto of the part to be tightened, and an operating lever extending through said slot and having its fulcrum pivotally connected to one of the gripping members at a point adjacent to the slotted wall and having means pivotally connected thereto beyond its fulcrum and pivotally connected to the other gripping element at a point adjacent to the slotted wall. 20

5. A tightening device comprising a hollow post having opposed parallel walls one of which is provided with a longitudinal slot, a pair of gripping elements within the post both extending in inclined directions transversely thereof between said parallel walls and engageable therewith, the length of said elements being greater than the distance between said opposed walls, one of said elements having means thereon for the attachment thereto of the part to be tightened, an operating lever extending through said slot and having its fulcrum pivotally connected to one of the gripping members at a point adjacent to the slotted wall and having means pivotally connected thereto beyond its fulcrum and pivotally connected to the other gripping element at a point adjacent to the slotted wall, said lever being movable into the slot in the post, and a releasing portion operative by the movement of said lever into said slot to swing one of the gripping members 30 into a more inclined position between said opposed walls and thereby release the grip of said element on said walls. 35

6. A tightening device comprising a hollow post having opposed parallel walls one of which is provided with a longitudinal slot, a pair of gripping elements within the post both extending in inclined directions transversely thereof between said parallel walls and engageable therewith, the length of said elements being greater than the distance between said opposed walls, one of said elements having means thereon for the attachment thereto of the part to be tightened, an operating lever extending through said slot and having its fulcrum pivotally connected to one of the gripping elements at a point adjacent to the slotted wall, a link pivotally connecting said lever at a point at one side of its fulcrum to the other gripping element at a point adjacent to the slotted wall, and means engageable with the gripping element having means thereon for the attachment thereto of the part to be tightened and operative by said lever to move said gripping element into a more inclined position between the opposed walls and thereby release it therefrom. 60 65
